UNITED STATES PATENT OFFICE.

WILLIAM FAUBION, OF GAUSE, TEXAS.

WINDMILL.

SPECIFICATION forming part of Letters Patent No. 711,954, dated October 28, 1902.

Application filed June 24, 1902. Serial No. 112,970. (No model.)

To all whom it may concern:

Be it known that I, WILLIAM FAUBION, a citizen of the United States, residing at Gause, in the county of Milam, State of Texas, have 5 invented certain new and useful Improvements in Windmills; and I do hereby declare the following to be a full, clear, and exact description of the invention, such as will enable others skilled in the art to which it applies 10 to make and use the same.

This invention relates to windmills; and it has for its object to provide a mill containing but few parts, which will be cheap and simple of manufacture and will be highly efficient.

A further object of the invention is to provide a construction wherein the wind-wheel may be entirely closed up when desired to protect it under extreme weather conditions.

20 Other objects and advantages of the invention will be understood from the following description.

In the drawings forming a portion of this specification, and in which like numerals of 25 reference indicate similar parts in the several views, Figure 1 is a section taken vertically through the tower and showing the mechanism therein in elevation. Fig. 2 is a transverse section through the upper portion of 30 the tower and showing the mechanism therein in plan view.

Referring now to the drawings, there is shown a windmill comprising a tower, the lower portion 5 of which is preferably 35 closed and is built over the well from which water is to be drawn by the mill, and upon the upper end of the portion 5 is a cupola 6, comprising the corner-uprights 7 and intermediate uprights 8, having vertical guide- 40 ways therein, in which slide doors 9, which may be raised to close the sides of the cupola or lowered to open them, the raising and lowering of the doors being effected by means of the ropes 10, passed over pulleys 11, secured 45 to the roof-beams 12 and attached to the doors. Upon the cupola is the roof 13, and at the peak of the roof is mounted a bearing-race 14. A hanger 15 is passed downwardly 50 through the race 14 and has a race 16 above the race 14, and between these races are ar-

ranged bearing-balls 17. Below the ball-bearing described is a second bearing 18, through which the hanger 15 is passed, and at the lower end of the hanger is the stirrup 19. In the stirrup 19 are bearings 20, in 55 which is journaled the wheel-shaft 21, and at the forward end of this wheel-shaft is fixed the wind-wheel 22, while at the extreme forward end is fixed the grindstone 23. To the stirrup 19 is attached a frame 24, comprising 60 sills and connecting cross-pieces, and on the cross-piece 25 is a bearing 26 for the rear end of the shaft 21. In the frame 24 is mounted the casing 27 of a grinding-mill, the casing containing a cylinder 28, a hopper 29 being 65 provided to receive the grain and direct it to the grinding-faces.

At the lower end of the stirrup 19 is mounted a shaft 30, carrying a gear-wheel 31, which engages a pinion 32 on the shaft 21, so that 70 the shaft 30 will be rotated from the wind-wheel. On the shaft 30 is fixed a drum 33, with which is engaged the belt 34, carrying buckets 35, and the belt hangs down into the well below the tower, so that as the shaft 30 75 is rotated the belt will be operated to raise the water and discharge it into a trough 36, which surrounds the belt below the shaft 30, this trough permitting the wheel to be swung to catch the wind and at the same time receiving the water from the bucket.

To insure the wheel remaining in the wind, a vane 37 is attached to the upper end of the hanger 15.

From the trough 36 leads a pipe 38 to a tank 85 39, that holds the water that has been raised from the well.

It will be seen that with this construction one or more of the doors of the cupola may be lowered to permit more or less of the breeze 90 to pass therethrough, and thus the speed of the wheel may be prevented from exceeding its proper point. Furthermore, the arrangement of the mechanism is such that the mill has many conveniences not ordinarily contained, it being understood that a drum 40 may be mounted upon the shaft 21 to receive a belt for transmitting energy.

In practice modifications of the specific construction shown may be made, and any suit- 100

able materials and proportions may be used for the various parts without departing from the spirit of the invention.

What is claimed is—

- 5 1. A windmill comprising a rotatable hanger, a wind-wheel having a shaft journaled in the hanger, a pump carried by the hanger and rotatable therewith, said pump being operatively connected with the wheel-shaft and a trough for receiving water from the pump, said trough surrounding the pump and mounted independently of the hanger.
- 10 2. A windmill comprising a tower having a cupola, a hanger passed vertically through the cupola and having a stirrup at its lower end provided with bearings, a shaft mounted in said bearings and having a wind-wheel fixed thereon, a second shaft mounted in the stirrup and operatively connected with the wheel-shaft, a drum upon the second shaft, a belt upon the drum and having buckets to receive and raise water, a trough surrounding the belt below the drum, and means for conveying water from the trough.
- 15 3. A windmill comprising a tower having a cupola, a hanger passed vertically through the cupola and having a stirrup at its lower end provided with bearings, a shaft mounted in said bearings and having a wind-wheel fixed thereon, a grinding-stone fixed to the shaft in advance of the wind-wheel, a frame connected to the stirrup, a grinding mechanism in the frame and comprising a cylinder mounted upon the wheel-shaft, a second shaft mounted in the stirrup and operatively connected with the wheel-shaft, a drum upon the second shaft, a belt mounted upon the drum and having buckets to receive and raise water, a trough surrounding the belt below the drum and means for conveying water from the trough.

3. A windmill comprising a tower having a cupola, a hanger passed vertically through the cupola and having a stirrup at its lower end provided with bearings, a shaft mounted in said bearings and having a wind-wheel fixed thereon, a grinding-stone fixed to the shaft in advance of the wind-wheel, a frame connected to the stirrup, a grinding mechanism in the frame and comprising a cylinder mounted upon the wheel-shaft, a second shaft mounted in the stirrup and operatively connected with the wheel-shaft, a drum upon the second shaft, a belt mounted upon the drum and having buckets to receive and raise water, a trough surrounding the belt below the drum and means for conveying water from the trough.

In testimony whereof I affix my signature in presence of two witnesses.

WILLIAM FAUBION.
